S. SAROSIER.
LIFE PRESERVING JACKET
APPLICATION FILED DEC. 13, 1915.

Patented July 12, 1916

UNITED STATES PATENT OFFICE.

STANISLAW SAROSIEK, OF NUTLEY, NEW JERSEY.

LIFE-PRESERVING JACKET.

1,191,836.

Specification of Letters Patent.

Patented July 18, 1916.

Application filed December 13, 1915. Serial No. 66,601.

To all whom it may concern:

Be it known that I, STANISLAW SAROSIEK, a subject of the Czar of Russia, residing at Nutley, in the county of Essex and State of New Jersey, have invented certain new and useful Improvements in Life-Preserving Jackets, of which the following is a specification.

This invention relates to certain new and useful improvements in life preserving jackets.

The primary object of the invention is the provision of a garment preferably in the form of a jacket or vest that may be readily slipped on and worn in case of danger from shipwreck and being provided with inflatable sustaining portions whereby the wearer is maintained afloat in the water.

A further object of the device is the provision of a vest that may be worn whenever desired and provided with air-receiving members easily inflatable by the wearer in the event of any possibility of danger from drowning.

25 The invention contemplates the provision of a closely fitting garment having an inflatable cushion positioned at the front and rear thereof and with a single inflation tube connected to the said cushions and into 30 which inflating air may be forced by means of the mouth and lungs of the wearer, a mouth-piece being arranged with a suitable check-valve and positionable wherever desired about the person.

35 With these general objects in view and others that will appear as the nature of the invention is better understood, the same consists in the novel construction, combination and arrangement of parts hereinafter more 40 fully described, illustrated in the accompanying drawings and then claimed.

In the drawings forming a part of this application and in which like designating characters refer to corresponding parts 45 throughout the several views:—Figure 1 is a perspective view of the complete device deflated. Fig. 2 is a transverse sectional view thereof through the air cushions arranged as operatively positioned upon the wearer, and, 50 Fig. 3 is a longitudinal sectional view through the mouth-piece and valve of the device.

By referring to the drawings, it will be at once apparent that the device broadly 55 consists of a vest 10 of substantially the

usual form and provided with stirring strings 11 at the waist-line thereof and with buttons 12 for reception within button-holes 13 in substantially the usual manner. An air cushion 14 is positioned at the rear of the vest being in the form of a receiving pocket 15 within which the rubber container 16 is inclosed, the said rear cushion being formed within the structure of the vest back 17.

A front cushion 18 of similar size and construction is permanently secured adjacent one front edge 19 of the vest and is adapted to overlap the opposite free edge portion 20 of the vest, being provided with button-hole tabs 21 for engagement with properly positioned buttons 22 upon the vest adjacent the arm-hole 23 at that side thereof.

A flexible connecting tube 24 of rubber or other desirable material is arranged between the cushions 14 and 18 and extends 75 over one of the shoulder portions 25 of the vest, being retained in position by means of tab members 35, while an inflating tube 26 communicates with the tube 24 and is provided with an inflating mouth-piece or nipple 80 27 upon its free end.

The nipple 27 is provided with a chamber 28 therein having a normally seated check-valve 29 having a seating spring 30 within the said chamber. The valve 29 is provided 85 with a stem 31 extending outwardly of the mouth-piece 27 and which may be readily depressed for opening the valve and allowing the air to escape from the cushions 14 and 18 through the tubes 24 and 26.

It will thus be evident that whenever desired, the mouth-piece 27 may be taken in the mouth of the wearer of the vest and by blowing into the same, the valve 29 will be unseated and the cushions 14 and 18 will be 90 filled with air and thus inflated to the desired extent sufficiently to maintain the wearer of the vest from sinking and being drowned if positioned within the water. A resilient retaining clip 32 is carried by the mouth-piece 27 being arranged with a band portion 33 resiliently received and slidably revoluble within an annular groove 34 of the said mouth-piece. By this arrangement, the mouth-piece 27 may be detachably secured to any portion of the vest or other garment, such as a pocket, not shown, and easily accessible by the wearer for the purpose of quickly inflating the supporting cushions 14 and 18 upon any occasion arising where- 110

by the wearer was in danger of shipwreck or drowning.

While the form of the invention herein shown and described is what is believed to be the preferred embodiment thereof, it is nevertheless to be understood that various forms, modifications and arrangements of the parts may be made without departing from the spirit and scope of the invention 10 as claimed.

What I claim as new is:—

1. A device of the class described comprising a vest, an inflatable cushion arranged within the body of the vest at the back portion thereof, a similar inflatable cushion having one edge thereof attached to one of the front side flat portions of the vest, buttonhole tabs on the opposite end of the said front cushion, engaging buttons for the said tabs carried by the opposite front side portion of the vest substantially beneath the adjacent arm portion thereof, an air tube attached over the shoulder portion of the vest and connecting the said cushions, an inflating tube having one end in communication with the said connecting tube, a valved inflating mouth-piece upon the opposite free

end of the said inflating tube, and a positioning clip carried by the said mouth-piece.

2. A device of the class described comprising a vest having closable front portions, an inflatable cushion permanently secured at one end to one of the said front portions and adapted for overlying both of said front portions when the device is operatively positioned with the vest in its closed arrangement, buttons carried by the said vest adjacent one of the arm portions thereof, button-hole tabs projecting from the free end of the said cushion and adapted for engagement with the said buttons, an inflating tube for the said cushion, a mouth-piece upon the free end of the said tube, a normally closed depressible check valve within the said mouth-piece, the said mouth-piece being provided with an annular groove, and a positioning clip for the tube and mouth-piece having a band member revolvably positioned within the said groove.

In testimony Whereof I affix my signature. 50
STANISLAW SAROSIEK.
